CLAIM

The ornamental design for a microwell plate, as shown and described.

DESCRIPTION

FIG. 1 is a perspective view of a first embodiment of a microwell plate.

FIG. 2 is a top view of the microwell plate.

FIG. 3 is a bottom view of the microwell plate.

FIG. 4 is a front view of the microwell plate.

FIG. 5 is a back view of the microwell plate.

FIG. 6 is a side view of the microwell plate.

FIG. 7 is another side view of the microwell plate.

FIG. 8 is a cross sectional view of the microwell plate taken along line 8-8 in FIG. 2.

FIG. 9 is an enlarged view of area 9 of FIG. 8.

FIG. 10 is a perspective view of a second embodiment of a microwell plate.

FIG. 11 is a top view of the microwell plate of FIG. 10.

FIG. 12 is a bottom view of the microwell plate of FIG. 10.

FIG. 13 is a front view of the microwell plate of FIG. 10.

FIG. 14 is a back view of the microwell plate of FIG. 10.

FIG. 15 is a side view of the microwell plate of FIG. 10.

FIG. 16 is another side view of the microwell plate of FIG. 10.

FIG. 17 is a cross sectional view of the microwell plate taken along line 17-17 in FIG. 11; and,

FIG. 18 is an enlarged view of area 18 of FIG. 17.
